WRITING DEVICE

Predrag Jovanovitsch, Maracay, Venezuela

Application November 10, 1947, Serial No. 785,016

Claims priority, application Switzerland
September 9, 1947

2 Claims. (Cl. 120—42.13)

1

This invention relates to an improvement in or for writing devices having two writing members arranged in a tube, which can be moved alternatively into their writing position, each of the writing members being equipped with an ink container.

In known writing devices, the writing members move only in the longitudinal direction, without changing their places in the tube. The aperture for the writing members is dimensioned with a cross section equal to the combined cross-section of the two writing members, consequently the writing members could not be securely held along the whole of their periphery. A further disadvantage is that when either of the two members is moved forward into its writing position, it is located on one side of the central longitudinal plane, so that by changing the writing members the writing device has to be turned through 180° in the hand.

All those disadvantages have been overcome by this present invention according to which the aperture for the writing members in the tube is so dimensioned as to fit closely round the section of the writing member, a guiding surface being thus formed, and the alternate forward movement of the writing members into the writing position is effected along a common axis.

The accompanying drawing shows one form of the writing device as carried out according to this invention.

Fig. 1 is a longitudinal section of the complete device,

Fig. 2 is a top plan view of one of the writing members with ink container,

Fig. 3 is a cross section on line 3—3 of Fig. 1, and

Fig. 4 is a right-hand view of Fig. 3, showing both ink containers without the tube housing therefor.

The tube 1 is provided with an eccentrically shaped aperture 2 through which either of the two writing members 3 or 4 can be pushed to assume writing position. The aperture is so dimensioned and shaped, that the respective end of each of the writing members, when in the position for writing, is completely encircled all around and guided by the wall defining aperture 2. In order to hold the writing member, which has been pushed forward into writing position, securely in this position, the wall of aperture 2 and the part of the writing member when placed in the aperture are defined by conical surface sections. An ordinary pen 3 and a ball point pen 4 are arranged in the tube of this writing

device. The two writing members 3 and 4 are fixed in the usual way in the tapered end of the ink containers 6 and 7, of semicircular section, the two flat sides of the said containers 5 abutting each other. The rear parts 6' and 7' of the containers, which are of reduced cross section, are located at the rear end of the tube 1 having a larger space, and are encircled by a rotatable bushing 8, which is held in the tube 1 by means of a pin 20 and a circular groove 21. The end of the bushing 8 protrudes beyond the tube 1 and is covered by a cap 9, firmly fixed to this bushing, the cap 9 serving to rotate the bushing 8. The cylindrical outer surfaces of the rear parts 6' and 7' of the ink containers are provided with helical grooves 10 and 11 respectively, converging toward each other, each of which embraces an arc of 180°, both ends of these helical grooves in the retracted positions 10 of the ink containers meeting at a common point (see Fig. 4). In the wall of the bushing 8 a ball 19 is fixed which engages at the forward junction 22 of the two grooves 10 and 11.

Each of the cylindrical surfaces of the two ink containers is provided with a groove 16a and 16b, respectively, of semicircular cross section running along the central line in the axial direction of the curved surface. Two transverse grooves, 12, 13 and 14, 15, respectively, each encompassing an arc of 90°, are cut in the center and at the front end of the cylindrical surface of the ink containers 6 and 7, joining the grooves 16a and 16b at right angles, the pair of central grooves 12, 14, and the pair of end grooves 13, 15, each completing a semicircle on opposite sides of the central longitudinal plane of the writing device. In the wall of the tube 1 are located two balls 17 and 18 in the central middle plane and diametrically opposite one another, so that in the retracted position of both writing members shown in Fig. 4, the ball 18 is at the front end of the groove 16a of the ink container 6 and is aligned with transverse end grooves 13, 15, and the ball 17 is at the middle of the groove 16b of the ink container 7, and is aligned with transverse middle grooves 12, 14.

By means of this arrangement of the balls and grooves, which are the guiding means of the writing device, when the bushing 8 is rotated through 180° to the right (clockwise as viewed in Fig. 3), since the containers 6 and 7 are prevented from rotating by the ball 18 engaging the wall of the longitudinal groove 16a opposite groove 13 and since ball 19 fixed to bushing 8 engages helical slot 10, the container 6 is moved forwards

3

in a longitudinal direction and the writing member 3 is moved forward to project from the tube 1.

Upon reversing the rotation of the bushing 8, rotation of the containers 6 and 7 is at first prevented by the ball 18, which is engaged in the groove 16a, until the container 6 and the cross groove 12 have been brought into their initial position; that is, until they have been screwed back so that the groove 13 faces the ball 18. On the bushing 8 being rotated another 180° to the left, the balls 18 and 17 engage respectively with the pairs of grooves 13, 15 and 12, 14, the pairs of grooves being then aligned with the balls 18 and 17, respectively, and rotation of the two ink containers 6 and 7 takes place. As a result of the rotation an exchange of the position of the two ink containers 6 and 7 takes place and in consequence also of the two writing members in the tube 1. On continuing rotation of the bushing 8 through 180°, the ink container 7 and with it the writing member 4 is moved forwards by the engagement of ball 19 of bushing 8 in helical groove 11 of member 4, and the member 4 is made to move through the aperture 5, as the two containers with their flat sides abutting each other are prevented from rotation by the ball 18 engaging in the longitudinal groove 16b. On reversing the rotation of bushing 8, the ink container 7 is first screwed back, as it is prevented from rotating by the ball 18 engaging in the groove 16b. On continuing the rotation, the process of turning and the forward motion of the other writing member occurs.

To fill the container 6 with ink, a plunger 26 operated by a screw-threaded piston 27, having a head 28, is provided, as indicated in the drawing. Access to the part 28 of the filling device may be had by removal of the cap 9, which is replaced after the filling operation. Some other known system may be used as well for filling. Suitable known organs, not shown, can also be provided for filling the ball point pen 4, 7. This writing device can be fitted with two ordinary pens or two ball point pens filled with different inks.

By means of this improvement of a writing device mere rotational movement causes a change of the writing members, which are moved forwards along their common longitudinal axis; also, in the case of two pens being provided, each pen is caused to move forward into its right position and securely held in the aperture of the writing device.

Having thus described the invention, what is claimed as new and desired to be secured by Letters Patent, is:

1. A writing instrument comprising a tubular housing having a front end provided with an aperture, a pair of writing elements in said housing, each of the elements having a sliding surface, said sliding surfaces abutting against each other, an operating structure rotatably connected to said housing and engaging both of said elements, each of said elements being adapted to assume a retracted position inside of the housing or an extended position in which an end of the respective element projects through the aperture, each of the writing elements having a set of grooves consisting of a helical groove, a coaxial groove and a pair of circumferential grooves, the coaxial and circumferential grooves communicating with one another, means on the operating

4

structure selectively cooperating with the helical grooves to advance and retract the writing elements, a projection in the housing co-operating with the co-axial and circumferential grooves of one of the writing elements to prevent rotation of said element while said element is located in a position with its forward part projected out of the housing, a second projection in the housing for preventing rotative movement of the other writing element while the latter element is in position with its forward part projected out of the housing, said projections being simultaneously registrable with the circumferential grooves in the writing elements when both the said writing elements are in a retracted position in the housing, whereby said writing elements can then be rotated within the housing.

2. A writing instrument comprising a tubular housing having a front end provided with an aperture, a pair of writing elements in said housing, each of the elements having a tip adapted for snug reception inside of said aperture, each of the elements having a sliding surface, said sliding surfaces abutting against each other, a rotatable operating member connected to the housing and engaging both of said elements, each of the elements being adapted to assume a retracted position inside said housing with its tip clear of the aperture, each of the writing elements having a set of grooves consisting of a helical groove, a co-axial groove and a pair of spaced circumferential grooves, the coaxial groove and the circumferential grooves being in communication, said rotatable operating member having a projection entering the helical grooves of both writing elements and acting to advance or retract either of said elements upon rotative movement of said operating member, internal projection within the housing cooperating with the coaxial and circumferential grooves in one of the members to prevent rotative movement of said member when said projection is located in its coaxial groove and to permit rotative movement of said member when said projection is in one of its circumferential grooves, a second projection in the housing for cooperation with the coaxial and circumferential grooves in the second writing element, said second projection preventing rotative movement of the second writing element when said projection is disposed in its coaxial groove and permitting rotative movement of said writing element when said projection is disposed in one of its circumferential grooves, the said projections being simultaneously registrable with the circumferential grooves in the writing elements when said writing elements are retracted into the housing whereby said writing elements may then be simultaneously rotated to bring one or the other to a position to be advanced in a projected position by rotative movement of the operating member.
